ABSTRACT OF THE DISCLOSURE

The disclosure relates to a vacuum relay comprising an envelope and an electromagnetic actuating assembly supported on the envelope. An armature is pivotally mounted within the envelope and a mobile contact mounted on the armature and movable therewith to make or break a circuit through a pair of fixed contacts. A resilient bracket is interposed between the envelope and the armature to resiliently retain the armature in operative position within the envelope. The armature contains a knife-edge about which the armature may pivot. Shield means are associated with each fixed contact to provide the deposition of vaporized contact material on the portion of the envelope through which each conductive lead extends.

The invention relates to vacuum relays, and particularly to a relay in which an armature is enclosed within a vacuum envelope and is made responsive to magnetic field generating means outside the envelope.

The conventional manner of supporting an armature within a vacuum envelope is to provide a hinge plate on which is hinged a spring-pressed armature. The necessity of maintaining close tolerances with this conventional construction is extremely difficult, and reciprocation of the armature through thousands of operations results in wear with attendant deviation from predetermined tolerances.

Accordingly, it is one of the objects of the invention to provide a spring-pressed armature for a vacuum relay in which there is no appreciable wear in the cooperating parts, thus precluding deviation from predetermined tolerances so as to increase the reliability of the relay.

It is another object of the invention to provide an armature assembly including a resilient bracket designed to retain the armature in position while imposing resilient bias thereon in a predetermined direction.

It is common practice in the vacuum relay art to utilize a dielectric envelope to support fixed contact members against which a movable contact may impinge to "make" a circuit through the relay. It has been found that rapid "make" and "break" operation of the relay results in the formation of a metal coating on the interior surface of the dielectric members, resulting from vaporization of contact metal. This has the deleterious effect of forming a conductive path over the surface of the dielectric member between the fixed contacts. Another problem incident to the support of such contacts on the dielectric envelope is the accommodation of varying thermal expansion rates between the dielectric and associated metallic leads supported thereon. Accordingly, it is a still further object of the invention to provide a shield and seal structure associated with each fixed contact which functions to prevent such deposition of vaporized contact metal on the dielectric envelope and at the same time functions to seal the metallic lead in the dielectric envelope in a manner eliminating the imposition of destructive stresses on the dielectric member.

The invention possesses other objects and features of advantage some of which with the foregoing will be apparent from the following description and the drawings.

2

It is to be understood however that the invention is not limited to the embodiment illustrated and described but may be embodied in various forms within the scope of the appended claims.

5 Referring to the drawings:

FIG. 1 is a side elevational view, portions of the structure being broken away to show the underlying parts.

FIG. 2 is a vertical cross-sectional view taken in the plane indicated by the line 2—2 in FIG. 1. Portions of the figure are shown in elevation for clarity.

FIG. 3 is a horizontal cross-sectional view taken in the plane indicated by the line 3—3 in FIG. 2.

FIG. 4 is a horizontal cross-sectional view taken in the plane indicated by the line 4—4 in FIG. 2. A portion of the resilient armature retaining bracket is broken away for clarity.

FIG. 5 is a fragmentary view in perspective illustrating the knife edge of the armature which defines the axis about which it is pivoted.

FIG. 6 is a fragmentary sectional view showing the bight for receiving the knife-edge of the armature. The angle through which the armature pivots is indicated by the arrows.

In terms of greater detail, the vacuum relay of the invention comprises a cylindrical dielectric envelope member 2, preferably ceramic, closed at its upper end by end plate 3 brazed to the metallized end-edges thereof, and closed at its lower end by a solenoid assembly designated generally by the numeral 4.

20 End cap 3 is provided with a suitable tubulation 6 for evacuating the interior of the envelope. The sealed-off tubulation is protected by encapsulating material 7 such as silicon rubber which is in turn covered by a metallic cap 8.

30 The solenoid assembly includes an outer magnetic housing member 9, within which is supported electromagnetic coil 10, provided with terminals 12 and 13 for connecting the coil to a source of electric power. The coil surrounds a core 14, the inner end of which extends into the envelope and is surrounded adjacent its inner end by a magnetic plate 16 which seals the inner end of the magnetic housing 9 and cooperates with a radially extending non-magnetic seal flange 17 to seal this end of the relay envelope in a vacuum tight manner. The outer peripheral edge of flange 17 is heliarc welded to the outer peripheral edge of a second superposed seal flange 18 brazed to the associated metallized end of the dielectric member 2.

40 As indicated best in FIGS 1 and 3, fixed conductive leads 21 and 22 extend through the dielectric envelope portion 2 in coaxial alignment and in a manner which will hereinafter be explained which eliminates the imposition of destructive stresses on the envelope due to differences in the thermal expansion characteristics of the parts. The inner ends of the leads 21 and 22 are spaced apart as 45 shown so as to constitute spaced fixed contacts and are adapted to be bridged by an electrically conductive bridging member or mobile contact 23 pivotally mounted on the inner end of a dielectric support rod 24. The lower end of the support rod is engaged by a resilient U-shaped bracket 26 to secure the support rod to a stud 27 brazed to armature 28.

on the sharp knife-edge 29 thereof. In order to prevent transverse displacement of the armature, the upstanding tab 32 is provided with an aperture 33, as shown best in FIGS. 2 and 4, and the knife-edge of the armature is provided with a lug 34, or portion of the edge not in knife-edge form, adapted to project snugly into the aperture.

To resiliently bias the armature away from the inner end of the core 14, i.e., to cause the armature to pivot upwardly as viewed in FIG. 2 about the knife-edge thereof as a fulcrum, a resilient bracket 36 is provided having a downwardly projecting bifurcated extension 37 engaging a notch 38 formed in the forward edge of the armature 10 opposite the knife-edge, as shown. The bracket 36 is bifurcated to control the resilience of the bifurcated extension and provide an opening through which support stem 24 and U-shaped bracket 26 may project. The other end 15 of bracket 36 is provided with a flange 41, the end of which is formed with an angularly disposed tab 42 appropriately caught in a slot 43 formed in the upstanding tab 32.

It will thus be seen that to assemble the armature assembly the knife-edge of the armature is inserted in the pocket 31, the extension 37 is engaged with the notched forward edge of the armature, and the lug 42 is engaged in aperture 43. If desired, the lug 42 may be engaged with the aperture 43 prior to engagement of the extension 37 with the forward edge of the armature. The resilient pressure exerted by the resilient bracket 36 retains the armature in assembled position and simultaneously normally biases it away from the inner end of the magnetic core 14. Upon energization of the coil 10, the magnetic field generated thereby attracts the armature down against the resilient force exerted by bracket 36 so that the inner end of the core 14 is abutted by the armature as shown in FIG. 2.

In order to prevent the deposition of vaporized contact metal on the inner surface of the dielectric envelope portion 2, the fixed contact portions of the conductive leads 21 and 22 are surrounded within the envelope by semi-spherical shields 44 and 45. Each shield is formed with its concavity facing the concavity of the opposing shield, with the adjacent edges of the shields being spaced apart a distance substantially equal to the spacing between the fixed contacts.

The concave shield shells are retained in position by a cylindrical extension 46 brazed to the contact rod as shown. The cylindrical extension is then expanded in diameter so as to provide an expanded cylindrical seal section 47 separated from the coaxially projecting lead by an annular space 48. The expanded diameter seal section is brazed in a vacuum tight manner within appropriate apertures 49 formed in the wall of the dielectric envelope portion 2. The wall thickness of the expanded diameter seal section is such that when brazed or welded to the associated lead the lead and shield form a rigid composite unit. The wall thickness is also gauged to be compatible with the wall thickness of the dielectric envelope

so that upon thermal expansion and contraction of the parts the dielectric material dominates the metal seal, thus preserving the integrity of the seal.

I claim:

1. A vacuum relay comprising an envelope closed at each opposite end, a plurality of conductive leads extending into the envelope to provide at least one pair of spaced fixed contacts within the envelope, an electromagnetic actuating assembly supported on the envelope and including an armature pivotally mounted within the envelope, a mobile contact mounted on the armature and movable therewith to make or break a circuit through at least one pair of fixed contacts, and a resilient bracket interposed between said envelope and the armature to resiliently retain the armature in operative position within the envelope, and shield means associated with each fixed contact to prevent the deposition of vaporized contact metal on the portion of the envelope through which each conductive lead extends, each said shield means including a semi-spherical hollow shell having a tubular extension projecting diametrically therefrom and coaxially arranged about the associated conductive lead, the end of said tubular extension remote from the semi-spherical hollow shell being united to the envelope in a vacuum-tight manner and an intermediate section of the tubular extension being reduced in diameter and united to the associated conductive lead in a vacuum-tight manner.

2. The relay according to claim 1, in which said armature is provided with a knife-edge about which the armature may pivot, abutment means within the envelope forming a bight in which the knife-edge of the armature is engaged, said resilient bracket retaining the armature in operative position having one end thereof anchored within the envelope and the other end engaging the armature to resiliently bias the knife-edge of the armature into the bight and bias the armature in a direction away from the electromagnetic actuating assembly.
